To all whom it may concern:

Be it known that I, Mildred Wagner, a citizen of the United States of America, residing in the city of New York, county of New York, and State of New York, have invented a new, original, and ornamental Design for a Dress Ensemble, of which the following is a specification, reference being had to the accompany drawing, forming part thereof.

Fig. 2 is a rear view thereof.

Fig. 3 is a front view of the dress member of the dress ensemble.

The characteristic feature of my design resides in the specific arrangement of the tucks on the upper and lower portion of the dress as shown in combination with the specific embroidery on the front jacket portion of the ensemble as shown.

I claim:

The ornamental design for a dress ensemble, substantially as shown and described.

MILDRED WAGNER.
